(57) **CLAIM**

The ornamental design for a computer monitor, as shown and described.

DESCRIPTION

FIG. 1 is a front, right perspective view of the computer monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a left side view thereof showing the monitor in a fully lowered position;

FIG. 9 is a left side view thereof showing the monitor in a raised and angled position; and,

FIG. 10 is a left side view thereof showing the monitor in a lowered and angled position.

The broken lines indicate portions of the computer monitor that form no part of the claimed design.

1 Claim, 10 Drawing Sheets
